Specification for Design.

Patented Jan. 1, 1918.

Application filed June 19, 1917. Serial No. 175,662. Term of patent 14 years.

To all whom it may concern:

Be it known that I, JOSEPH LAWTON, a citizen of the United States, residing at Trenton, in the county of Mercer and State of New Jersey, have invented a new, original, and ornamental Design for a Grave-Marker, of which the following is a specification, reference being had to the accompanying drawing, forming part thereof.

Figure 1 of the drawing is a front elevation of a grave marker with the upright or stake partially broken away, illustrating my new design, and Fig. 2 is a side elevation thereof.

I claim:

The ornamental design for a grave marker, as shown.

JOSEPH LAWTON.
